UNITED STATES PATENT OFFICE.

JOHN L. AXEN, OF CHICAGO, ILLINOIS.

DESIGN FOR A RADIODESK.

Application filed May 28, 1924. Serial No. 9,723. Term of patent 3½ years.

To all whom it may concern:

Be it known that I, JOHN L. AXEN, a citizen of the United States, residing at Chicago, county of Cook, and State of Illinois, have invented a new, original, and ornamental Design for a Radiodesk, of which the following is a specification, reference being had to the accompanying drawing, forming a part thereof, wherein—

The desk is shown in perspective elevation.

What I claim and desire to secure by Letters Patent, is:—

The ornamental design for a radiodesk, as shown.

Signed at Chicago, Cook County, Illinois, this 20th day of May, 1924.

JOHN L. AXEN.
